ATTORNEY-

UNITED STATES PATENT OFFICE

ERHARD NICOLAUS WEBER, OF NEW YORK, N. Y.

SAFETY RAZOR

Application filed July 13, 1932. Serial No. 622,233.

This invention relates to new and useful improvements in a safety razor. It is particularly adapted to razors generally sold in the market under the name of "Gillette" and "Probak" and similar types.

The invention has for an object the construction of a safety razor which is characterized by identification adapted to avoid the excess use of one and the same edge of a

blade. As a further object it is proposed to arrange the identification so that it may be remembered easily which edge has been used the last and the most.

Furthermore, it is proposed to arrange the identification so as to know exactly from which edge to expect satisfactory service and a good shave.

Another one of the objects of this invention is the arrangement of a blade guard for location beneath the blade of the safety razor and having a projection engaging into a larger size aperture in a blade holding plate so that said aperture has the simultaneous function of also exposing an identification mark on the blade of the razor and holding said projection.

Furthermore as another object it is proposed to arrange the top of the projection at an inclination to reduce its obstruction of the identification mark.

Furthermore, as another object of this invention it is proposed to provide the blade holding plate with openings adapted to expose markings upon the blade to identify the various edges.

This invention still further proposes the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an end elevational view of a safety razor constructed according to this invention.

Fig. 2 is a plan view of Fig. 1.

Fig. 3 is a fragmentary sectional view taken on the line 3—3 of Fig. 2.

Fig. 4 is a plan view of a razor constructed according to a modification of the invention.

Fig. 5 is a plan view of the blade used in the razor shown in Fig. 4.

Fig. 6 is a fragmentary view similar to a portion of Fig. 2, but illustrating a modified construction.

Fig. 7 is a sectional view taken on the line 7—7 of Fig. 6.

The safety razor according to this invention comprises a blade holding plate 10 for location above a safety razor blade 11 and having cutouts 12 for the double function of exposing a portion 13 of the blade 11 and for receiving a projection 14 from a blade guard 15 for location beneath the blade 11. The blade holding plate 10, the blade 11 and the blade guard 15 are held together in conventional fashion and attached upon the handle 16 to conclude the formation of the razor. The blade guard 15 is formed with a plurality of teeth 17 along its edges as is customary.

The projections 14 engage against the sides of the openings 12 so as to firmly hold the relation of the blade and the blade holding plate and the blade guard. The projections 14 are so arranged that at one end they are spaced from the end of the openings and thus provided for the space through which the identification on the blade may be viewed.

Preferably, though not as a limitation, the identification should be numerals or letters denoting the different edges of the blade. Moreover they should be placed on both sides of the blade to identify the sides in addition to the edges. As shown in Fig. 2 the openings 12 are arranged on opposite sides of the longitudinal center line in a manner so that the blade may be engaged in place as shown in the drawing or with the cutting edge now at the top, placed at the bottom. The top surfaces of the projections 14 are inclined,

see Fig. 3, so as to remove some of the obstruction from viewing the identification in

the openings 13 from positions other than directly over the openings.

In Figs. 4 and 5, a modification of the invention has been disclosed in which a razor is shown to include a blade holding plate 22 for location above the blade 21. The latter mentioned element of the blade, is formed with identification marks 23 identifying the edges thereof and the blade holding plate 22 is formed with openings 24 arranged to be superimposed on the indications 23, clearly shown in Fig. 4, and whereby the edges of the blade may be identified. Particular attention is called to the location of the openings 24 which are spaced in from the edges of the blade holding plate, in distinction with the openings of the previous form which are cut in from the edges of the blade holding plate.

In Figs. 6 and 7 another modification of the invention has been disclosed in which the blade guard 15 is formed with projections 14' similar to and for the same purpose as the projections 14 in the first described form, excepting the projections 14' are formed with hollowed out tops 25. Record cards 26 are attached over the tops of the projections 14' and held by screws 27. These record cards are printed with a plurality of boxes 28 adapted to be punched by a pin indicated by the dot and dash lines 29 to keep a record of the shaves taken on each edge. The material of the record card 26 should be thin celluloid, cardboard, or the like so as to be easily punchable. In other respects the invention is identical to the first described form and corresponding parts may be recognized by corresponding reference numerals. One screw 27 is sufficient to hold each of the record cards 26, in that the edges of the record cards engaged against the sides of the openings 12.

The razors constructed according to this invention may be used in conventional fashion excepting that records or the memory may be used to avoid excess use of one and the same edge of the blade to identify which edge has been used last and most and to know exactly which edge to expect satisfactory service and a good shave.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. In a safety razor, a blade holding plate for location above a razor blade and having a cutout, a blade guard for location beneath the blade and having a projection adapted

to extend through a cutout in the blade and to extend into said cutout of the blade holding plate and against the sides thereof and of smaller length than said cutout so that a small area of the blade is exposed and adapted to be provided with edge indicating characters.

2. In a safety razor, a blade holding plate for location above a razor blade and having a cutout, a blade guard for location beneath the blade and having a projection adapted to extend through a cutout in the blade and to extend into said cutout of the blade holding plate and against the sides thereof and of smaller length than said cutout so that a small area of the blade is exposed and adapted to be provided with edge indicating characters, said cutout in the blade holding plate being extended in from one side and said projection engaging into the opening through the opened side.

3. In a safety razor, a blade holding plate for location above a razor blade and having a cutout, a blade guard for location beneath the blade and having a projection adapted to extend through a cutout in the blade and to extend into said cutout of the blade holding plate and against the sides thereof and of smaller length than said cutout so that a small area of the blade is exposed and adapted to be provided with edge indicating characters, said projection having an inclined top.

4. In a safety razor, a blade holding plate for location above a razor blade and having cutouts, a blade guard for location beneath the blade and having projections adapted to extend through cutouts in the blade and to extend into said cutouts of the blade holding plate and against the sides thereof and of smaller length than said cutouts so that a small area of the blade is exposed and adapted to be provided with edge indicating characters.

5. In a safety razor, a blade holding plate for location above a razor blade and having a cutout, a blade guard for location beneath the blade and having a projection adapted to extend through a cutout in the blade, to extend into said cutout of the blade holding plate and against the sides thereof and of smaller length than said cutouts so that a small area of the blade is exposed and adapted to be provided with edge indicating characters, and a record card attached upon the top of said projection, said projection being hollowed out to allow convenient punching of the record card.

In testimony whereof I affix my signature.
ERHARD NICOLAUS WEBER.
